PREPARATION OF UNSATURATED HYDROCARBONS

Rupert C. Morris and Robert J. Moore, Berkeley, Calif., assignors to Shell Development Company, San Francisco, Calif., a corporation of Delaware

Application June 15, 1942, Serial No. 447,138

4 Claims. (Cl. 260—630)

This invention relates to a process for the preparation of unsaturated hydrocarbons from petroleum distillates and, more particularly, aromatics such as benzene, toluene and xylene, and diolefines such as butadiene, isoprene, and other homologous diolefines.

It has heretofore been proposed to separate toluene or other aromatics from natural or cracked petroleum distillates by concentrating the aromatics by way of distillation to obtain a fraction containing upwards of 5% aromatics, and by extracting the resulting concentrate while in the vapor phase with a suitable selective solvent to obtain pure or substantially pure aromatics, and a raffinate substantially free from toluene.

It has also been proposed to subject this raffinate to various treatments in order to produce therefrom more useful products. Thus, for example, it has been proposed to subject the aromatic-free raffinate to vapor phase cracking at a temperature above about 1100° F. whereby aromatics and diolefines are produced; and to recover these valuable hydrocarbons.

It is an object of this invention to improve the yields of valuable hydrocarbons having conjugated double bonds, and particularly of toluene, and of butadiene and pentadiene which may be obtained by thermal cracking of aromatic-free raffinates obtained in the recovery of toluene or other aromatics from concentrates derived from natural or synthetic petroleum distillates. Further objects will be found in the improvements hereinafter disclosed.

This invention is based on the discovery that subjecting to an isomerizing treatment the non-aromatic hydrocarbons normally associated with and boiling close to the aromatics, prior to thermally cracking them, greatly improves the yields of valuable hydrocarbons obtained therefrom.

According to the present invention, at least a portion of the substantially aromatic-free raffinate obtained after recovery of the aromatic from the concentrate is subjected to an isomerizing treatment followed by thermal cracking in the vapor phase above about 1000° F., whereby an unusually high proportion of aromatics and dienes is formed. These hydrocarbons are then separated, and preferably from the remainder of the cracked product a naphtha fraction may be produced which is recycled through the system.

A hydrocarbon fraction to be suitable for the purpose of this invention is one in which has been concentrated the major amount and preferably

substantially the entire amount of a single aromatic hydrocarbon or a single group of metamerized aromatic hydrocarbons, e. g., benzene, or toluene or xylenes and ethyl benzene, etc., which amount was originally contained in the hydrocarbon distillate under treatment. This fraction or concentrate should have a boiling range as narrow as possible consistent with the requirement of containing the major portion of the aromatic, and it should be substantially free of components boiling above or below the boiling range over which the aromatic boils when the fraction is subjected to a close fractional distillation. In producing these suitable concentrate fractions, highly efficient fractional distillation equivalent at least to 20 theoretical plates at a reflux ratio of 2:1 should be employed. Such narrow fractions are preferably produced by continuous fractionation and if so produced will, in general, upon being subjected to analytical distillation, show at least 95% boiling within the following ranges:

	Concentrate containing	Maximum range	Preferred range
25		°F.	°F.
	Benzene.....	156-185	164-178
	Toluene.....	195-245	206-231
	Xylenes and ethyl benzene.....	260-300	267-290

30 Analytical distillation as herein defined is a laboratory batch distillation operated over 30 equilibrium plates and at a reflux ratio of at least 20:1.

35 For the purpose of our invention the composition of the concentrates may be said to consist of 3 component parts: (1) an aromatic or a group of metamerized aromatic hydrocarbons, (2) non-aromatic hydrocarbons which form upon cracking large amounts of dienes, and (3) non-aromatic hydrocarbons which do not give such high yields of dienes. These three components cannot be separated from each other by simple fractional distillation, i. e., distillation conducted in the absence of added separating agents, and in order to effect a separation it is necessary to distill the concentrates in the presence of a selective solvent for one of the components of the aromatic hydrocarbons. However, after separation of aromatics, 40 simple fractional distillation is capable of separating the two kinds of non-aromatic hydrocarbons, the lower boiling fraction containing those which give originally lower yields of dienes and are particularly improved by our invention.

45 50 55

It will be apparent that narrower fractions than

above-described may be used with advantage but will give lower overall yields of the desired dienes as calculated on the total distillate. The inclusion of small amounts of higher or lower boiling hydrocarbons, however, will give inferior results, the extent of depreciation depending upon the amount of these hydrocarbons included. Such variations may be produced, for example, by less efficient fractionation of the petroleum distillate when producing the narrow boiling fractions.

Fractions boiling in the above range and particularly in the preferred range, allow the separation of pure aromatics practically free of other hydrocarbons and boiling within 1° F.

The nature of the invention will be better understood from the following detailed description, taken together with the drawings forming a part of this specification which illustrate certain preferred embodiments thereof, in which:

Figure I is a flow diagram illustrating a particularly preferred form of the improved process; and

Figure II is a flow diagram illustrating the isomerization step of this process.

Figure III is a flow diagram illustrating the general steps of the process.

For simplicity the drawings do not show pumps, heat exchangers, valves, by-passes, vents, re-boilers, condensers, and other auxiliaries, the proper placement of which will be at once evident to those skilled in the art.

Referring to Figure I, illustrating a particularly preferred form of this invention: A hydrocarbon feed containing toluene and a large proportion of non-aromatic hydrocarbons whose boiling temperatures range from below to above that of toluene is introduced at 1 from a source not shown into fractional distillation zone 3. This feed may be of any provenience, natural or synthetic, cracked or straight-run. In order to facilitate the isomerization step of this process, it is advantageous that the feed be substantially free of olefines; thus straight-run gasoline which contains appreciable quantities of toluene is preferred. Toluene-rich naphthas produced in the process, as hereinafter described, may be added thereto through line 5. In the fractionating zone 3 a "concentrate" containing most of the toluene of the feed and having a boiling range as narrow as practicably possible is produced and taken through line 7 while substantially toluene-free higher and lower boiling portions are withdrawn through lines 9 and 11. The "toluene concentrate," or "concentrate" for short, boils between about 190° F. and 245° F. and preferably between about 205° F. and 230° F., toluene boiling at 231.4° F. Hydrocarbons having nearby boiling points form azeotropes with toluene and the boiling range of these azeotropes varies with the nature of these hydrocarbons, being in general comprised in the above limits. It is usually desirable to produce a concentrate having a toluene content of 5% and preferably 8% or more, and this may require adjusting the boiling range of the concentrate to the nature of the particular feed. It was found that from an East Texas straight-run gasoline a concentrate containing from 8% to over 10% of toluene and boiling from about 206° F. to about 230° F. could be obtained, while from West Texas straight-run gasoline a concentrate containing from 10% to over 15% of toluene and boiling from about 208° F. to 228° F. could be obtained.

The toluene concentrate hereinabove described is led through line 7 into separation zone 13 wherein substantially pure toluene is recovered and a substantially toluene-free fraction is ob-

tained. This latter fraction will hereinafter be called "toluene-free raffinate" or "raffinate" for short. This raffinate may contain small amounts of aromatics of the order of 1% or 2% because of practical limits upon the degree of separation which can be attained. This small proportion does not interfere with the subsequent steps of this process. Larger proportions of toluene such as those which are originally present in the toluene concentrate, e. g., 5% and up, are detrimental, particularly in the isomerization. In the latter operation, toluene is retained by the catalyst and inactivates it rapidly, for example, by dilution or complex formation in the case of liquid catalysts or of sludge formation in the case of solid catalysts.

A cracked toluene concentrate produced in the process as will be described may be introduced through line 15 and treated in toluene recovery zone 13 concurrently with the above-mentioned toluene concentrate. The separation of toluene from the raffinate will be more fully discussed hereinafter.

The toluene is withdrawn through line 17 and the raffinate is led through conduit 19 to be isomerized and cracked. Prior to isomerization the raffinate may be fractionated in fractional distillation zone 21, so as to separate fractions which are most benefited by isomerization from those that may advantageously by-pass the isomerization step of this process, to be directly subjected to cracking conditions.

It is often advantageous to separate from the raffinate a relatively high boiling fraction boiling above about 210° F. and preferably above 215° F., which is led directly into cracking zone 21 through lines 23 and 25. The remaining lower boiling portion of the raffinate, or if this fractionation step is omitted, the entire raffinate, is conducted through line 29 into isomerization zone 31.

The isomerization step of this process is designed to so modify the structure of hydrocarbons contained in the raffinate that on subsequent cracking they produce larger amounts of aromatics and dienes than could otherwise be obtainable. It has been found that conditions under which isomerization takes place substantially without cracking or dehydrogenation are especially suitable. In such an operation the composition of a mixture of hydrocarbons always shifts towards a state of equilibrium between the components, and it is preferred to continue the operation until this equilibrium is substantially reached. This equilibrium composition may vary very appreciably with temperature, so that isomerization of a hydrocarbon mixture at a high temperature may produce the opposite change from isomerization at low temperature. Thus isomerization should be conducted at a temperature below about 800° F. and preferably 400° F. The isomerization step will be more fully discussed hereinafter and a preferred embodiment will be described with reference to Figure II.

The isomerized raffinate may advantageously be combined with the unisomerized fraction obtained through line 23 as previously described, or a recycle fraction hereinafter described introduced through line 24, or both. The combined stream is led through line 25 into cracking zone 27 where it is vaporized and heated rapidly to a peak temperature of 1000° F. to 1450° F., and preferably 1300° F. to 1400° F., in order to crack it, whereby unsaturated hydrocarbons such as olefines, dienes, and aromatics are formed. The resulting cracked vapors are immediately cooled

or quenched at 33. The time of cracking at these high temperatures is governed so as to gasify about 30% to 80% of the feed per pass, gasification being defined as conversion of the liquid feed to molecules having 5 or less carbon atoms.

The degree of gasification which is a measure of intensity of cracking affects greatly the nature of cracked products. If the cracking is relatively mild, i. e., corresponding to a gasification below about 45%, the normally liquid portion of the cracked products will comprise a predominant proportion of unchanged raffinate, while the gases, particularly the C₄ and C₅ portion, comprise major amounts of dienes. If, on the contrary, the cracking is relatively severe, i. e., corresponds to a gasification above about 65%, the liquid portion comprises major amounts of aromatics, particularly toluene, which are apparently formed mainly by secondary reactions from the olefines first produced. At the same time the amount of dienes formed is slightly higher, their concentration in the respective fractions substantially being unchanged, and the proportion of these fractions in the gasified products being greatly reduced. Upon increasing cracking intensities, particularly in the intermediate range, i. e., upon increasing gasifications from about 45% to 65%, the amount of unchanged raffinate in the liquid product decreases markedly and the proportion of aromatics increases.

As compared with the unintensified stock, at any given gasification or cracking conditions the conversion to valuable hydrocarbons having conjugated double bonds is unusually high under otherwise comparable conditions.

Of particular advantage is the high concentration of C₄ and C₅ dienes in the respective C₄ and C₅ fractions. Thus, for example, the amount of pentadienes found in a C₅ fraction may be as high as 60%. This greatly facilitates the recovery of the dienes, as it is relatively simple to separate C₄ and C₅ fractions but it is difficult and costly to subsequently separate the dienes from the other hydrocarbons having nearly equal vapor pressures.

The heating of the hydrocarbons to the cracking temperature may be achieved by contact with a heated solid surface, for example in an externally heated coil, or may be realized by admixture of hot, substantially inert gases such as flue gases, carbon dioxide, hydrocarbon gases, steam, etc., or by a combination of both methods.

In order to prevent excessive coke formation it is often desirable to avoid the contact of ferrous metals with the hydrocarbon at cracking temperatures. Copper-containing alloys such as aluminum or phosphor-bronze, or refractory ceramic materials do not cause rapid coking when used in the construction of surfaces exposed to hydrocarbons at cracking temperature.

Cracking according to this invention is preferably purely thermal, i. e., non-catalytic, and is conducted in the absence of catalyst, be it added catalysts such as gaseous halogenated compounds, solid catalytic metals or oxides, or catalysts preformed in situ, e. g., lustrous carbon or pyrophoric metals.

The cracking is advantageously conducted at pressures of about atmospheric or below and preferably not substantially above 100-150 lbs. p. s. i. Pressures not substantially in excess of those required to overcome the back pressure of the cracking unit are desirable.

The actual time for which the vapors are subjected to cracking conditions is very difficult to

estimate correctly because of volume variations during cracking, but should not exceed about 0.1 second to avoid cracking the butadiene formed. The liquid space velocity is, however, easy to estimate and, for given temperatures, pressures and admixtures, determines the actual vapor space velocity and cracking time. Liquid space velocity is the volume of liquid delivered per hour to the cracking zone, per volume unit of said zone. The cracking zone is defined as the space occupied by gases in which the temperature is within 20° C. of the peak temperature.

The liquid space velocity necessary to obtain a given gasification depends on the temperature and pressure in the cracking coil. At 775° C. and atmospheric pressure, for example, a liquid space velocity of about 60 results in gasification of about 60%.

Resuming the description of Figure I, the cracked and quenched products are led through line 35 into a fractional distillation zone 37 wherein several fractions required for the recovery of the several valuable hydrocarbons, as well as a recycle naphtha, are produced. Gases lighter than C₄ which are rich in olefines may be withdrawn through line 39 and tars and heavy materials through line 41. C₄ and C₅ gases rich in dienes are led through line 43 to zone 45 wherein the dienes are advantageously recovered, for example, by extractive or azeotropic distillation, or by solvent extraction by means of a polar solvent having greater solvent power for dienes than for mono-olefines and saturated hydrocarbons, or by selective polymerization, or by complex or compound formation, or by a combination of these methods, etc.

A naphtha substantially free of C₅ and lighter hydrocarbons is withdrawn from zone 37 through line 47. The composition of this cracked naphtha depends greatly on the severity of cracking conditions as has already been mentioned.

If the cracking is mild, this cracked naphtha predominates in unchanged cracking stock and may advantageously be recycled to cracking zone 15 27 through lines 47 and 24.

If the cracking is severe the cracked naphtha contains toluene in addition to other non-aromatic hydrocarbons, and it is advantageous to recycle it to the toluene recovery system, i. e., zones 50 3 and 13. This may be effected through lines 47, 49 and 5. Alternately, a toluene concentrate may be prepared by fractional distillation of the naphtha in zone 37, higher and lower boiling components being withdrawn through lines 51 and 53. This cracked toluene concentrate may be recycled directly to separation zone 13, through lines 47, 49 and 15.

The cracked naphtha or cracked toluene concentrate may contain substantial amounts of olefines, and particularly polyolefines, produced in the cracking. Olefines have a polarity intermediate between that of paraffinic hydrocarbons and of toluene. This makes it more difficult to separate olefines, and especially polyolefines, than to separate paraffins from toluene in separation zone 13. Furthermore, once separated from the toluene, olefines form part of the toluene-free raffinate and interfere with the proper functioning of many isomerization catalysts in zone 34. To overcome this difficulty the raffinate may be freed of olefines after being separated from the toluene, or as preferred, the olefines may be separated from the cracked naphtha or concentrate prior to the recovery of toluene. The latter can be done in zone 55 by methods which eliminate or trans-

form preferentially polyolefines or poly- and mono-olefines without substantially affecting aromatics and paraffins. Such methods are, for example, absorption in dilute acids such as sulfuric acid or complex-forming reagents, e. g., Cu_2Cl_2 , AgCl , etc.; hydrogenation in the presence of a suitable catalyst such as nickel, copper, etc.; polymerization followed by fractionation, especially catalytic polymerization, in the presence of suitable catalysts such as solid phosphoric acid or one of those listed in National Petroleum News of November 20, 1935, page 45 and following, or in U. S. Patent 2,171,207; partial oxidation in the presence of a catalyst such as silver, etc., followed by fractional distillation, etc.; or a combination thereof.

The resulting substantially olefine-free cracked product containing toluene may then be conducted through line 51 and recycled through either line 5 or line 15, as previously described, to the toluene recovery zones 3 and 13.

The separation of toluene in zone 13 may be effected by any suitable means, treatment with polar solvents having preferential solvent power towards aromatic hydrocarbons being the most suitable. This treatment with solvents may take the form of liquid-liquid extraction or azeotropical distillation, extractive distillation, or the like. Extractive distillation, i. e., extraction of a vapor phase by means of a higher boiling polar liquid, being both highly effective and economical, is a preferred method.

Extractive distillation may be performed by means of two columns, the polar solvent being introduced at the top of the first one while vapors containing toluene are fed at intermediate points and toluene-rich solvent is obtained at the bottom. In the second column the toluene-rich solvent is stripped of toluene which is obtained overhead and the regenerated solvent obtained as bottom product may be fed to the first column. Suitable refluxing and reboiling means are used in both columns to insure efficient separation.

The relative height on the first column of inlets for the two toluene concentrates of this process, i. e., the one obtained directly from separation zone 3 through line 7 and the cracked concentrate which may be obtained through line 15, depends upon their contents of toluene. The richer one will always be introduced below the poorer one for best results.

The most practical polar solvents suitable for extractive distillation are phenol, cresols, various mixtures of alkyl phenols, aniline, alkyl anilines, diphenyl amine, ditolyl amines, carbitols (diethylene glycol mono ethers) such as methyl, ethyl, and propyl carbitols, chlorinated dialkyl ethers such as beta-beta-dichlorethyl ether, nitrobenzene, nitrotoluene, nitroxylenes, naphthols, alkyl naphthols, benzo phenone, phenyl tolyl ketone, diphenyl ketone, alkyl phthalates such as dimethyl phthalate, alkyl salicylates such as methyl salicylate, benzyl alcohol, benz chlorides, i. e., benzyl, benzal, and benzo chlorides, benzonitrile, diphenyl oxide, ditolyl oxide, hydroxy pyridine, nitropyridine, chlorinated pyridines, quinoline, isoquinoline, chlorinated quinoline, hydroxy quinolines, 5-nitro quinoline, tetra hydro furfuryl alcohol, furfural alcohol, furfural, the mono glycerol ethers such as 1-methoxy glycerol, 2-methoxy glycerol, 1-ethoxy glycerol, 2-ethoxy glycerol, 1-propoxy glycerol, 2-propoxy glycerol, 1-isopropoxy glycerol, and 2-isopropoxy glycerol, the glycerol di-ethers such as 1,2-di-methoxy glycerol, 1,3-di-methoxy glycerol, 1,2-di-ethoxy

glycerol, 1,3-di-ethoxy glycerol, 1,2-di-propoxy glycerol, 1,3-di-propoxy glycerol, 1,2-di-isopropoxy glycerol, and 1,3-di-isopropoxy glycerol, the mixed di-glycerol ether esters such as 1-ethoxy - 2 - methoxy glycerol, 1 - methoxy - 3 - propoxy glycerol, and 1-ethoxy-2-isopropoxy glycerol.

It has been already pointed out that the isomerization step is essential to this process and is performed in zone 31 on at least a part of the raffinate prior to cracking. Isomerizing conditions capable of transforming naphthenes having 5 carbon atom rings into hydrocarbons having 6 carbon atom rings, e. g., methyl cyclopentane to cyclohexane, have been found suitable for the purpose of this invention. This isomerizing step will now be described more fully.

Isomerization may be effected by contacting the hydrocarbons with a suitable catalyst under conditions depending on the nature of the catalyst. Thus, for example, molybdenum sulfide or oxide may act as an isomerization catalyst in the vapor phase at 400° C. to 450° C. in the presence of a large proportion of hydrogen. It is preferred, however, to utilize at a lower temperature Friedel-Crafts catalysts, e. g., the halides of Al, Zr, etc., in the presence of a hydrogen halide promoter and, if desired, hydrogen.

Preferable isomerization catalysts are those comprising anhydrous aluminum chloride and/or aluminum bromide. Of these, aluminum chloride is preferred since it is less expensive, easier to employ and has much less tendency than aluminum bromide to cause degradation of hydrocarbons. Other acid-acting catalysts of the Friedel-Crafts type may also be employed if desired in conjunction with the aluminum chloride. The catalyst may, if desired, be employed as a solid, either in suspension in the liquid reaction mixture or as a fixed bed. In the latter case it is preferably employed as lumps, granules or pellets of suitable size, preferably deposited upon or mixed with a suitable solid support. Particularly effective catalysts are produced when aluminum chloride is supported upon or intimately mixed with one of the various preferably adsorptive siliceous and/or aluminous materials of natural or synthetic origin which contain an appreciable amount of firmly-bound water. Suitable materials of this category are, for example, the naturally-occurring minerals and clays such as pipe clay, bauxite, fuller's earth, bentonite, Florida earth, meerschaum, kaolin, infusorial earth, Kieselguhr, diatomaceous earth and the like; the various treated clays and clay-like materials such as "Tonsil," "Celite," "Sil-O-Cel," "Terrana" and the like; and artificially prepared materials such as "Activated Alumina," silica gel, the artificial permutites and the like. These materials are preferably heated in a dry atmosphere at a moderately elevated temperature, such, for instance, as about 400° C. to 800° C., until they substantially cease to give off water. Although these materials produce preferred catalysts when combined with aluminum chloride, other supporting materials such as activated carbon, coke, crushed brick, pumice and the like may also be used.

While solid catalysts may be suitably employed, an improved and advantageous method has been developed whereby the isomerization treatment may be effected in a continuous manner using liquid catalysts. Particularly suitable liquid catalysts are those of the Gustavson (C. Z. 1903 II, 1113) and Ansolv (German Patent No.

535,473) acid types wherein aluminum chloride is in combination with various organic compounds such as organic acids, ethers, esters, hydrocarbons, etc., and those of the metal double-salt type in which the aluminum chloride is in loose combination with, or solution in, similar metal halides such, for instance, as the halides of Sb, Ti, Na, K, Li and the like. By employing aluminum chloride in combination with certain of these metal halides, excellent isomerization catalysts may be prepared which melt to free-flowing liquids at very moderate temperatures and may be pumped through the reaction system with or countercurrent to the hydrocarbon fraction to be isomerized. The use of liquid catalysts in the isomerization has definite advantages. The raffinate to be treated often contains small amounts of aromatic and/or olefinic hydrocarbons. These hydrocarbon types, if present, are generally quite detrimental when employing fixed beds of catalysts. When employing fluid catalysts, hydrocarbon fractions containing small amounts of olefines or aromatic hydrocarbons may be treated without difficulty, though large amounts of either are always detrimental. These liquid catalysts, moreover, have a considerably milder action and in general are much less prone to cause degradation of hydrocarbons. Also, they allow the isomerization to be effected in simple apparatus in a continuous and most practical manner.

A flow diagram of a suitable isomerization unit employing this principle is illustrated in the attached Figure II. Referring to Figure II, the hydrocarbon to be treated is fed through line 29 into a surge tank 61 and from there via pump 62 to a circulating pump 63 wherein it is mixed with a liquid catalyst and promoter and circulated through a heater 64 and time tank 65, and back to the circulating pump 63 via a valved line 66. The time tank 65 is preferably equipped with perforated baffles or other means to insure thorough contact between the hydrocarbon and liquid catalyst. All or a portion of the material passing through time tank 65 is withdrawn to a separating device 67 wherein the liquid catalyst is separated from the bulk of the hydrocarbon. The liquid catalyst from separator 67 is recycled to the circulating pump 63 via valve 68 and line 66. A portion of the partially spent liquid catalyst may be continuously or intermittently removed if desired via valved outlet 69 and an equivalent amount of fresh catalyst may be added via pipe 70. The hydrocarbon separated from the catalyst in separator 67 is passed through a cooler 71 and filter 72 wherein any particles of suspended catalysts are removed, and is then passed to tank 73.

The assembly of apparatus illustrated diagrammatically in Figure II is adapted for the use of liquid catalysts of the above-mentioned Gustavson or Ansolvo acid types. The catalyst may be prepared in any conventional manner and supplied to the system, for instance, via line 70. For the sake of completeness the preparation of the catalyst is also shown in the flow diagram of Figure II. The apparatus provided therefor and which may be considerably modified if desired, comprises a mixing vessel 74 interconnected in a circulatory system via circulating pump 75 to a small chamber 76. Aluminum chloride or other catalyst is charged to the mixing vessel 74 and a quantity of the organic material to be reacted therewith to form the complex catalyst is intro-

duced via line 77. This may be any one or a mixture of a great number of organic compounds. In case the complex catalyst is one of the Gustavson type (C. Z. 1903 II, 1113) the liquid added 5 may be an aromatic hydrocarbon or a hydrocarbon mixture rich in aromatic hydrocarbons. Aromatic hydrocarbons, as a class, are generally suitable. Thus, for example, benzol and the various alkyl derivatives thereof may be used. Particularly suitable catalysts of this type may be prepared from the so-called bright stocks or Edeleanu extracts obtained by the extraction of aromatic-containing distillates with sulfur dioxide. These catalysts are found to contain approximately twice as much aluminum chloride, for example, as catalysts of the same general type prepared from benzol or toluol. They therefore have a much longer life. Catalysts of this type are described in U. S. Patents Nos. 1,671,517, 20 1,586,357, 1,999,345, and British Patent No. 7,112 (1914). Complexes prepared with extracts or unextracted distillates are also useful.

The isomerization treatment is preferably executed in the presence of a hydrogen halide promoter such, for example, as hydrogen chloride. The amount of promoter preferably employed depends upon the activity of the catalyst and the prevailing temperature, and may vary from a small amount such as about 0.05% up to several 25 per cent. In one preferred method of operation, wherein the hydrocarbon fraction is treated in a continuous manner in the liquid phase, a considerable excess of hydrogen chloride (for example, a partial pressure of hydrogen chloride vapor of at least 1 to 3 atmospheres) is employed and the hydrogen chloride is recycled through the reaction zone. Thus, in Figure II the product from tank 73 is forced via pump 78 to a stripping column 79 wherein the HCl promoter and any other lower-boiling material is taken off overhead. The overhead fraction is passed through a cooler 80 into a vessel 81. Condensed liquid in vessel 81 is pumped back to the stripping tower to serve as reflux. The bottom product from tower 79 is passed through a caustic scrubber 82 to remove any last traces of promoter and is then stored in tank 83 from which it is conducted to the cracking step of this process through line 25. The hydrogen chloride promoter separated from the product in the stripping column is recycled back to the isomerization system via line 88. The hydrogen halide (and hydrogen, if this is used) recycled to the system is preferably passed through a drier 86 containing a suitable drying agent such as CaCl_2 , P_2O_5 , activated alumina, or the like. Small amounts of excess gas may be vented from time to time by valved outlet 87. Make-up hydrogen chloride is supplied to the system from any convenient source such as a high-pressure cylinder 84.

As pointed out above, however, when using liquid catalysts the isomerization process may be executed with only very small amounts of hydrogen chloride promoter, for instance, less than 1%. In such cases, it may be more economical not to attempt to recover and recycle the promoter. In this case the product from tank 73 may be simply caustic-washed and sent to storage. Instead of feeding in hydrogen halide per se, the hydrogen chloride or other hydrogen halide promoter may be carried to the reaction zone, dissolved in one of the reactants, or may be generated in the reaction zone from added materials which under 65 the reaction conditions react or decompose to lib-

erate hydrogen halide. Suitable materials which may be added for this purpose are, for example, organic halides such as organic alkyl halides, organic hydroxy compounds such as the various phenols and alcohols, inorganic salts containing molecularly-bound hydrogen halide such as $\text{PbSO}_4 \cdot 2\text{HCl}$, $\text{CuSO}_4 \cdot 2\text{HCl}$ and the like.

The isomerization with Friedel-Crafts catalysts may be effected over a wide range of temperatures depending upon the space velocity, concentration of promoter employed and upon the activity of the catalyst. Although temperatures ranging from about room temperature up to about 500° F. may be employed, the isomerization may be effected economically at quite moderate temperatures such, for example, as from about 160° F. to 400° F. In some cases, especially when the catalyst is particularly active or the temperature is somewhat high, it may be found that the isomerization is accompanied by appreciable amounts of side reactions. This may be easily remedied, if it occurs, by slightly decreasing the temperature or concentration of promoter, or if desired, by effecting the isomerization treatment in the presence of hydrogen. Hydrogen, if employed, may be conveniently recycled with the hydrogen halide promoter. Although the use of hydrogen is not generally necessary, provision for its use is shown in Figure II. Thus, if hydrogen is recycled along with the promoter, make-up hydrogen may be added from cylinder 85.

Referring now to Figure III which illustrates an application of this process in which one concentrate, e. g., the benzene or the toluene or the xylene concentrate, or any two concentrates, or the three concentrates simultaneously, are being treated. It will not be described in regard to the last-mentioned case, it being understood that by proper variation of the flow scheme any other case may be realized.

A hydrocarbon distillate containing aromatics is admitted from storage not shown through line 91 to fractional distillation zone 92. A suitable distillate produced in the process may be admitted thereto through line 93. In this fractionation zone 92 the admitted distillates are fractionated to produce the desired narrow boiling concentrates and separate them from the remainder of the distillate. The concentrates may be conducted through lines 94, 95 and 96 to aromatic separation zone 97. The remainder may be withdrawn through lines 98, 99, 100 and 101. If an aromatic is present in traces only it may by-pass the aromatic separation zone 97. Thus, for example, the benzene cut may be conducted through lines 102 to line 104 in which the benzene-free benzene raffinate may be obtained from separation zone 97. In both cases (i. e., whether the benzene has been separated or not) this cut may be advantageously separated in fractional distillation column 105 into two substantial fractions, a bottom portion boiling above 170° F., which is withdrawn through line 106, and an overhead fraction obtained through line 47 and conducted to line 44.

The other aromatic-free raffinate may be obtained through lines 108 and 109 which lead, as well as line 104, to isomerization zone 110.

A fractionation step to separate the raffinate into two portions, both forming a substantial part thereof, one higher and one lower boiling, and to by-pass the latter around the isomerization zone may be effected also on the toluene and xylene raffinate. In zone 110 the three raffinates are

isomerized under conditions substantially as described above for toluene. They may be commingled through line 111 and isomerized together, but it is preferred to effect the isomerization separately because of different optimum conditions of isomerization of the several raffinates.

The isomerized raffinates or their fractions are withdrawn from zone 110 by lines 112, 113 and 114, respectively, and are advantageously commingled with the higher boiling part of the raffinate which has by-passed the isomerization zone. Thus, for example, the part of the benzene raffinate boiling above 170° F., which has been obtained through line 106 from fractional distillation column 105, is commingled with the isomerized part boiling below 170° F., conducted through line 112. In the cracking zone 115 three fractions are cracked under conditions similar to those previously described for the toluene concentrate in cracking coils 116, 117 and 118. It is preferred to crack the fractions under independently controlled conditions of time and temperature, as their thermal stability is different, the lower boiling ones being less stable and requiring greater liquid space velocities for the same gasification. If desired, the several concentrates may be combined by means of line 119 and cracked together in one coil.

The cracked products after rapid quenching are treated in separation zone 120 to separate therefrom dienes which may be withdrawn through line 121, an aromatic-rich naphtha having a broad boiling range taken through line 93 to zone 92, or one or more cracked concentrates taken through lines 122, 123 and 124 to zone 97; and other hydrocarbons may be withdrawn at 125 or 126.

Olefines which may interfere with the separation of aromatics or cracking may be separated in separation zone 127 as described above.

The following examples may further serve to illustrate this invention.

Example I

45 A toluene-free raffinate was obtained from a West Texas toluene concentrate boiling from 206.6° F. to 230° F. One part of this raffinate was cracked without isomerization and another was cracked after being subjected to isomerization 50 in the presence of a toluene-aluminum chloride liquid catalyst at 194° F. at a liquid space velocity of 1 volume of raffinate per volume of catalyst per hour, and in the presence of 0.1% of HCl.

55 Both feeds were cracked in an "ambraloy" tube filled with quartz chips at a temperature of 1427° F. and the results summarized in the following table.

	Isomerized raffinate	Unisomerized raffinate
Liquid space velocity	61	70
Gasification	59	53
Butadiene produced wt. % on feed	4.7	3.2
Pentadiene produced wt. % on feed	6.4	4.3
Butadiene produced wt. % of gas phase	8.0	5.5
Pentadiene produced wt. % of gas phase	10.9	7.3
Butadiene produced wt. % of C ₄ cut	40.3	26.4
Pentadiene produced wt. % of C ₄ cut	60.0	52.5

Example II

A xylene-free xylene raffinate obtained from a West Texas naphtha boiled from 125° F. to 142° F. One part of it was cracked at 1382° F. without any

further treatment, and another part was isomerized in the presence of toluene-aluminum chloride catalyst at 176° F. at a liquid space velocity of 1 volume of raffinate per volume of catalyst per hour and in the presence of 0.1% HCl, and then cracked under the same conditions as the first part.

The former yielded 12.8% of dienes in the gas phase, while the latter yielded 16%.

We claim as our invention:

1. An improved process for manufacturing conjugated diolefins from a relatively narrow boiling hydrocarbon fraction boiling within the range of 150° to 290° F. from which substantially all the aromatics have been removed, comprising the steps of fractionally distilling said fraction to produce higher boiling and lower boiling portions, isomerizing the lower boiling portion, combining the isomerized product with said higher boiling portion, cracking the combined product in the

vapor phase above 1000° F. for a time to gasify 20% to 80% thereof, whereby substantial amounts of conjugated diolefins are produced, and separating said diolefins from the resulting products.

2. The process of claim 1 wherein said narrow boiling fraction boils between 156 and 185° F. and from which substantially all of the benzene has been removed.

3. The process of claim 1 wherein said narrow boiling fraction boils between 195 and 245° F. from which substantially all of the toluene has been removed.

4. The process of claim 1 wherein said narrow boiling fraction boils between about 260 and 300° F. from which substantially all the xylenes and ethyl benzene have been removed.
